PIVOTED HOUSING FOR AN ANCHOR

Laverne O. Persinger, Burbank, Calif., assignor of
fractional part interest to Merle L. Persinger

Filed Nov. 28, 1969, Ser. No. 20,298

Term of patent 14 years

Int. Cl. D12—16

U.S. Cl. D71—1

Fig. 1

Fig. 3

FIG. 1 is a perspective view of a pivoted housing for an anchor in stowed position, showing my new design;
 FIG. 2 is a side elevational view;
 FIG. 3 is a rear elevational view;
 FIG. 4 is a top plan view; and
 FIG. 5 is a side elevational view, similar to FIG. 2, showing the housing in anchoring position.

I claim:

The ornamental design for a pivoted housing for an anchor, as shown and described.
